UNITED STATES PATENT OFFICE.

JOHN W. DURR, OF PORTLAND, OREGON.

MANGLE.

SPECIFICATION forming part of Letters Patent No. 760,530, dated May 24, 1904.

Application filed September 22, 1903. Serial No. 174,150. (No model.)

To all whom it may concern:

Be it known that I, JOHN W. DURR, residing at Portland, in the county of Multnomah and State of Oregon, have invented certain new and useful Improvements in Mangles, of which the following is a specification.

My invention relates to improvements in mangles; and it more particularly seeks to provide an attachment to be used in connection with an ordinary type of mangle; and the invention primarily has for its object to provide means to prevent the adhesion of the goods to the presser-rollers.

In its generic nature the invention comprehends a series of endless cord belts which take around the presser-roller and pass in the direction of the circumference of the main drum to near the first apron-roller.

With this and other objects in view, which will be hereinafter apparent, the invention consists in certain novel combination and arrangement of parts, all of which will be first described in detail and then be specifically pointed out in the appended claims, reference being had to the accompanying drawings, in which—

Figure 1 is a vertical longitudinal section of the mangle with my invention applied. Fig. 2 is an enlarged diagrammatic view illustrating the arrangement of the presser-rollers, the drum, and the apron-rollers with my invention applied. Fig. 3 is a top plan view of the main drum and the lower presser-roller with my invention applied. Fig. 4 is a top plan view of the shaft with its sheaves detached. Fig. 5 is a detail view of the bracket member and its end bearing. Fig. 6 is a sectional view of one of the pulleys *i*, showing the manner in which the pulleys are retained in position on the rod *e*.

Referring now to the accompanying drawings, in which like letters of reference indicate like parts in all the figures, A indicates the stationary heating-drum mounted on the main frame A', around a portion of which the carrying-apron Y passes, which apron Y is of the endless variety and takes around the apron-rollers U, E, and V, and which is tightened or loosened with respect to the drum A

by means of a lever D and rod D' and roller E, as shown.

N designates the feed-box, and O the first covered roller, which coöperates with the upper steam-chest P, while the second covered roller R coöperates with the steam-chest S, and T designates the discharge-table, all of which is clearly shown in Fig. 1 and which may be of the ordinary construction, as they *per se* form no part of my present invention.

From practical experience I have found that the goods (designated by G) when it passes between the second covered presser-roller R and the steam-chest S will stick to the roller R and become tangled and be wound around said roller R instead of traveling downward to the apron Y. The rollers O and R are in practice covered with several thicknesses of cloth and press against the steam-chests P and S, and I have found that no trouble is experienced in the goods sticking to the roller O, and it passes freely to the roller R; yet owing to the space between the roller R and the roller U the goods will stick to the roller R, and unless some means be provided to loosen the goods from the roller R the goods will be wound upon said roller and damaged. I have therefore devised means to obviate this objectionable feature and to guide the goods from the roller to the apron Y and prevent its sticking to the said roller R.

To the projection *f* of the drum A, I fasten the adjustable arms or brackets *a*, which have elongated apertures *b* to receive the bolts *b*, which arms are bent in the curve of the drum A and have end bearings *c* to receive the rod *e*, which is secured to the bearings *c* by nuts *e'*. Mounted at suitable intervals along the rod *e* are a number of sheaves or pulleys *i*, around which the roller R takes a cord *k*, which may be of the ordinary cotton cord, such as is used to tie up bundles. These pulleys *i* are mounted to turn loosely on the stationarily-held rod *e* and are prevented from endwise movement and are held in proper position by the pins *x*, which pass through apertures *y* in the rod *e*, as clearly shown in Fig. 6.

As the rollers O and R are in practice

wrapped with a cloth covering σ and τ , the cord k will sink into the cloth, and all danger of producing a crease in the goods is avoided.

So far as described the operation of my invention will be best explained as follows: The goods G is fed from the box N and the roller O , which, rotating in the direction of the arrow m , will carry the goods between itself and the steam-chest P toward the roller R , which roller R , rotating in the direction indicated by the arrow n , will then carry the goods between itself and the steam-chest S to the drum A . Should the goods become stuck to the roller R , the cords k will release it, and it then passes downward to the roller U . Upon reaching the roller U the apron Y carries it in the direction of the arrow z to the discharge-table T . (See dot-and-dash lines, Fig. 1.)

From the foregoing description, taken in connection with the accompanying drawings, it is thought the complete operation and advantages of my invention will be understood by those skilled in the art to which it appertains. I desire it understood that slight changes in the detail arrangement and construction of parts may be made without departing from the scope of the appended claims.

Having thus described my invention, what I claim, and desire to secure by Letters Patent, is—

1. In a mangle, a heating-drum, and an apron and apron-rollers for coöperating therewith, a presser-roller mounted adjacent said drum, said presser-roller being covered with yielding material, a rod running parallel with the axis of the heating-drum, a plurality of suitably-spaced sheaves rotatably mounted upon the said rod, endless cords passing over

said sheaves and said presser-roller, and means for tightening the said cords so that they become embedded in the yielding cover of the presser-roller, said means including adjustable bracket members having bearing portions to receive said rod and mounted on the main heating-drum, for the purposes specified.

2. In a mangle, a main heating-drum, an endless apron and apron-rollers coöperating therewith; an adjacent presser-roller, a yielding cover therefor, said drum having projections, bracket members adjustably mounted on said projections and extending toward the endless apron, said bracket members having bearing portions, a rod held in said bearing portions, sheaves mounted on said rod at suitable intervals, and endless cord belts passing over said sheaves and said adjacent presser-roller, for the purposes specified.

3. In a mangle, a main heating-drum, an endless apron, coöperating therewith, an adjacent presser-roller having yielding covering, said drum having projections, bracket members adjustably mounted on said projections and extending toward the endless apron in the arc of the circumference of the heating-drum, said bracket members having bearing portions, a rod held in said bearing portions, sheaves loosely and rotatably mounted on said rod at suitable intervals, said sheaves being held away from the heating-drum, and endless belts passing over said sheaves and said adjacent presser-roller, for the purposes specified.

JOHN W. DURR.
